ELECTRICAL ADVERTISING DEVICE

Cecil H. Coffrin, Brooklyn, and Florence J. McCarthy, Hewlett, N. Y., assignors of one-third to Sele S. Pike, New York, N.Y.

Application June 6, 1939, Serial No. 277,572

6 Claims. (Cl. 177—346)

The object of the present invention is to provide an electrical display apparatus comprising a sign board supporting a plurality of contiguous electric lamps, the lamps being in circuit with a control board, and the combination being such as to create on the sign board by means of electric lamps the illusion of skywriting.

The invention will be described with reference to the accompanying drawings, in which:

Figure 1 is a plan view, somewhat diagrammatic as to the designation of electric contacts and other elements illustrating an embodiment of the control board.

Figure 2 is a plan view, somewhat schematic, illustrating an electric sign controlled by the board.

Figure 3 is a view in elevation illustrating the control board of Figure 1 at the forward end thereof.

Figure 4 is an enlarged fragmentary view of the control board and the motor-driven circuit closing member which simulates an airplane, part of the latter being broken away.

Figure 5 is a longitudinal section on the line 5—5, Figure 1, looking in the direction of the arrows and showing the circuit closing member in action.

Figure 6 is a view similar to Figure 5, showing the position of certain switch elements after a movement of the circuit closing member.

Figure 7 is a fragmentary section on the line 7—7, Figure 1.

Figure 8 is a schematic wiring diagram.

Referring to Figures 1 and 2 there is shown, as indicated generally by A, an electric control board, and at B an electric sign controlled thereby.

Carried by the sign B are a plurality of closely associated electric lamps as indicated at 1 and, if desired, the letters or other matter to be produced in simulation of skywriting, by the illumination of certain lamps, are, in the required areas, represented by electric lamps 2 which may be tinted to differentiate them from the lamps 1 or which may be contrasted with the lamps 1 by the tinting of the latter. This contrasting coloration of the lamps however, is not essential.

The control board will carry spring switch members as indicated at 6 and 10, these members being equal in number to the lamps for illumination on the sign board. The control board also carries on a trackway of any suitable construction, as indicated at 4, a propelled circuit closing member 5 adapted to move on the trackway 4.

The mutual arrangement of the control board

and the lamps of the electric sign is such that as the circuit closing member moves along the trackway, circuits leading to the electric sign will be closed so that lamps in the form of an airplane will be illuminated, and the airplane will appear to move over the sign board leaving behind it illuminated lamps in the form of the desired sign, which thus appears progressively as in skywriting. When the completed sign is formed the airplane, shown by the appropriate illuminated lamp, moves away therefrom and finally the sign disappears due to the opening of the circuit or circuits leading to the letters or pictorial matter thus produced.

By reference to Figure 1, it will be seen that the circuit closing member is in the form of an airplane and by reference to Figure 6 it will be seen that as the circuit closing member moves to the left it will depress the spring switch members 6 within its area and that as it moves on it will release said switch members which spring up and break the circuit formerly closed. Thus only the area bounded by the circuit closing member, and in the form of an airplane, will act upon the switch member 6.

Each spring switch member 6 is, when operated, brought into contact with a contact post 7 (Figure 6) having a branch wire 8 leading to the appropriate lamp 1, the spring switch member being suitably grounded and the lamps receiving current via wire 9.

The lamps 2 forming the desired sign, when illuminated, are controlled by the circuit closing member 5 through the instrumentality of the spring switch member 10 adapted to be moved into engagement with the contact posts 11 (Figure 5), each post being connected as by a wire 12 to a feed wire 13 and the spring switch members 10 being suitably grounded. Each spring switch member 10, when moved to circuit closing position by the circuit closing member 5 remains in such position until the circuit closing member moves away from the completed sign formed by the lamps 2 and reaches a predetermined point in its travel on trackway 4. To such end the control board carries under each spring switch member 10 a lower power magnet 14 through which a circuit may be effected via wires 15 and 16, the arrangement being such that when each spring switch member 10 is moved down into engagement with its contact post 11, the magnet 14 will hold it in that circuit closing position until the circuit through wires 15, 16 is broken. The wires 15, 16 lead up to the magnets 14 via branch wires 15x, 16x.

The construction of the circuit closing member is shown in Figures 4 and 7. Mounted thereon is a motor 18 driving a worm 19 in engagement with a worm gear 20 connected in any suitable manner to an axle 21 for the forward set of wheels 22 of the circuit closing member or one of said wheels. In the present embodiment, as shown in Figure 7, worm gear 20 is in mesh with the gear 23 carried by axle 21 for one of the wheels 22. As shown in Figure 7, the 10 right hand track element is insulated so that it may carry electric current leading to the motor. The positive motor lead is indicated at 27 and the negative lead at 28. To lead 27 is connected a finger 21z which will ride on the adjacent insulated track element and that track element is connected to positive wire 29. It will be understood that the wheel 22 will be made of suitable non-conducting material. The negative lead 28 may be connected to a finger 28x riding upon the left-hand track element which may serve as a ground.

Projected upwardly above the surface of the control board A is a stud shaft shown at 24 in Figures 1 and 3. Thus when the circuit closing member has completed the production of an illuminated sign and passes beyond the same it will meet stud shaft 24 and momentarily open the circuit leading to the magnets 14 by separating contact members 25 and 26, comprising a switch disposed in lead wires 16. The magnets being de-energized, spring switch arms 10 will move upwardly to break the circuit through the lamps 2, and when in the continued movement of the circuit closing member it passes stud shaft 24, spring action of one of the contact members 25, 26, will re-engage them to close the circuit through the wires 15 and 16. The low power magnets 14, however, will have no action upon contact arms 10 until they are again depressed by the circuit closing member.

In the operation of the circuit closing member its position throughout its movement will appear on the board B by an illumination of lamps conforming with the shape of said circuit closing member, in this instance an airplane. As the airplane circuit closing member moves in an area corresponding with any area of the sign to be shown by the lamps 2, it will be followed by illumination and retention of illumination of the lamps 2 so the effect will be that of an airplane leaving a visual trail, as in skywriting. To augment the effect, the trackway is preferably so formed as to correspond with the path of travel customarily followed by an airplane in skywriting, the selected advertising sign, in this instance, being I. J. Fox.

It will be understood that the form and arrangement of the elements comprising the embodiment of the invention illustrated in the drawings may be substantially varied without departing from the spirit of the invention, what we claim and desire to secure by Letters Patent, being as follows:

1. An electrical advertising sign incorporating means for producing the effect, by illumination, of progressive transcription of skywriting by an illuminated airplane representation performing the transcription comprising a carrying member, electric lamps supported by said carrying member, a control device having a plurality of switches, each electrically connected to a lamp on said carrying member, a circuit closing member shaped as an airplane and adapted for movement over the switch devices to progressively close the same,

and means for holding part of said switch devices in closed position after the withdrawal therefrom of said circuit closing member, the remaining switch devices moving to open position upon said withdrawal therefrom of the circuit closing member, and the closed switches continuing the illumination of the lamps connected thereby to simulate the progressive formation of a skywriting signed delineation.

2. An electrical advertising sign constructed in accordance with claim 1, in combination with a trackway on the control board, means for propelling the circuit closing member on said trackway and means on the control board at a predetermined position relatively to the path of movement of the circuit closing member, and in electrical connection with said switch holding means, for rendering said switch holding means inactive.

3. An electrical advertising sign incorporating means for producing the effect, by illumination, of skywriting, comprising a carrying member, closely spaced electric lamps supported by said carrying member, a control device having a plurality of sets of switches, each electrically connected to a lamp on said carrying member, a trackway, a circuit closing member adapted for movement on said trackway over the sets of switches to progressively close areas thereof conforming with the shape of an airplane, and means for holding one set of said switches in closed position after the withdrawal therefrom of said circuit closing member, the remaining switch devices moving to open position upon the withdrawal therefrom of the circuit closing member, and the closed switches continuing the illumination of the lamps connected thereby to simulate the progressive formation of a skywriting signed delineation.

4. An electrical advertising sign constructed in accordance with claim 3, in which the trackway is endless, in combination with means adjacent the trackway and adapted to be engaged by the circuit closing member for rendering the switch holding means inactive.

5. An electrical advertising sign constructed in accordance with claim 3 in which means for holding part of the switches in closed position comprise an electric circuit, a magnet for each of the switches which are adapted to be held in closed position, and a circuit opening member disposed in the pathway of the circuit closing member and adapted to be opened by engagement therewith of the circuit closing member.

6. An electrical advertising sign incorporating means to produce the effect, by illumination, of skywriting, comprising a carrying member, electric lamps supported by said carrying member, a control board having a plurality of switches, each electrically connected to a lamp on said carrying member, a trackway conforming to the desired skywriting, a plurality of said switches being disposed closely adjacent the trackway, a switch closing member in the shape of an airplane, a power device for driving the switch closing member on a trackway, the latter being continuous, an electrical holding device for part of said switches which are disposed closely adjacent the trackway, a circuit common to all of said electrical holding devices, and a circuit breaking device for said last-named circuit, adapted to be actuated by the circuit closing member in its movement.
